UNITED STATES PATENT OFFICE.

WILLIAM A. SHELY, OF CHICAGO, ILLINOIS.

MACHINE FOR TREATING OR BREAKING AND SCUTCHING HEMP OR OTHER FIBROUS MATERIAL.

1,410,416.

Specification of Letters Patent. Patented Mar. 21, 1922.

Original application filed July 1, 1918, Serial No. 242,888. Divided and this application filed June 12, 1919. Serial No. 303,608.

To all whom it may concern:

Be it known that I, WILLIAM A. SHELY, a citizen of the United States, residing in Chicago, in the county of Cook and State of Illinois, have invented certain new and useful Improvements in Machines for Treating or Breaking and Scutching Hemp or other Fibrous Material.

This invention relates to that class of machines for breaking and scutching or treating hemp or other fibrous material, having a break-bar or a plurality of break-bars adapted to engage hemp or fibrous material to be operated upon, and provided with beater mechanism adapted to operate upon and break and scutch or treat and clean hemp or fibrous material fed into position to be engaged by such break-bars, or fiber-supporting element and beater mechanism.

The principal object of the invention is to provide a simple, economical and efficient machine for breaking and scutching or treating and cleaning hemp or other fibrous material; and one of the purposes of the invention is to provide such a machine with beater mechanism adapted to enable the material operated upon to be struck with the desired degree of force and by means of beater-bars or beater members moving in the desired direction with respect to the fibrous material, and to enable the beater-bars, blades or beater members by means of which the scutching or cleaning of the fibrous material is accomplished, or by means of which the breaking and scutching of such material is accomplished, to engage and move lengthwise of and in engagement with the fibrous material in such a manner as to scutch and clean or remove the hurds or shives from the fibrous material without unduly breaking or injuring the fibres, and with facility.

A further object of the invention is to provide a machine for breaking and scutching hemp or similar fibrous material, with beater-mechanism comprising beater-bars or beater-blades adapted to extend transversely with respect to fibrous material or hemp stalks to be operated upon and to engage or strike such material while the beater bars are moving in the desired direction with respect to the stalks or fibrous material to cause the shives or hurds to be broken and loosened from the outer fibres in an efficient manner,

and, by a continuous and uninterrupted movement of the beater-bars substantially, longitudinally of and in frictional engagement with the fibers or fibrous material for the desired distance lengthwise of the stalks or fibers, and, by preference, with beater-bars simultaneously on in rapid alternation, in scutching engagement with the stalks or fibers on opposite sides of the same, so as to flex the fibers to the desired extent without injury thereto and thoroughly scutch and clean the same, the breaking and scutching being progressive lengthwise of the stalks, and both carried on at the same time.

Other and further objects of the invention will appear from the following description and claims, and from an inspection of the accompanying drawings, which are made a part hereof.

The invention consists in the features, combinations, and construction and arrangement of parts and cooperating elements herein described and claimed.

In the accompanying drawings:

Figure 1 is a view in side elevation, of a machine constructed in accordance with my invention;

Fig. 2, is a plan view of the same, with a front portion of the feed table broken away, and with other parts of the machine broken away at the central portion of the machine, the transverse parts which are shown broken, being of much greater length than that shown in said figure, in proportion to the length of the machine from front to rear;

Fig. 3, is a view in central longitudinal vertical section, taken on line 3 of Fig. 2, looking in the direction indicated by the arrow.

This application is a division of a pending allowed application Serial No. 242,888, filed July 1, 1918, by me and in my name, for an improvement in machines for treating or breaking and scutching hemp or other fibrous material, and subject matter of invention herein described and not claimed will be found described and claimed in said application.

In constructing a machine for breaking and scutching or treating hemp or other fibrous material, in accordance with my invention I provide a main frame which may be of any desired suitable form, and, when constructed as shown in the accompanying

drawings, comprises main longitudinal side frame members 1, 2, transverse frame members 3, upright side-frame members 4, 5, 6 and 7, on one side of the machine, and corresponding upright side-frame members 8, 9, 10 and 11 on the opposite side, the side-frame members 4 and 8 being directly opposite each other, the side-frame members 5 and 9 being directly opposite each other, frame-members 6 and 10 being directly opposite each other and back of the members 5 and 9, and the members 7 and 11 being directly opposite each other at the rear portion of the main frame, all of said frame members being rigidly secured together and made of suitable material, such as metal or wood—preferably metal—and forming a strong and rigid frame capable of supporting the movable parts of the machine and of withstanding the shocks and strains to which the machine is subjected when in operation.

Mounted at or near the forward extremity of the machine is a pair of parallel break-bars 12 and 13 which are in superposed relation and extend transversely and, by preference, horizontally across the machine, said break-bars being spaced apart, so as to provide a space 14 therebetween adapted to permit hemp stalks or stalks of fibrous material to be operated upon to be fed into position to extend between and in engagement with the bottom fiber engaging or stalk-breaking margin or edge 1 of the upper break-bar 12, and the upper fiber-engaging or stalk-breaking edge 16 of the lower break-bar 13. (See Figs 1 and 3.) The break-bars 12 and 13 are supported at their opposite ends by suitable supporting means, such, for instance, as the upright side frame members 4 and 8, to which the corresponding ends of said break-bars are secured in any desired ordinary or suitable manner, but, by preference in such a manner as to permit the break bars to be adjusted with respect to each other, as well as upward and downward and forward and backward, each independently, to any desired adjusted position upon the machine frame. This may be accomplished in a simple and efficient manner by mounting each end of each of the break-bars 12 and 13, upon and in horizontally adjustable relation to a vertically adjustable supporting member 17, the vertically adjustable break-bar supporting members 17 each being secured to and in vertically adjustable relation to a suitable stationary support such, for instance, as the adjacent upright side frame member 4 or 8 or similar suitable support. The vertically adjustable supporting members 17 are each provided with one or more vertically elongated slots 18 through which extend horizontal screws or bolts 19 which are anchored in the adjacent stationary support-

ing frame member, such as the adjacent frame member 4 or 8 on the corresponding side of the machine. Each of said break-bars is provided with an angular end portion 20 extending forward with respect to the main body of the bar and in adjustable or slidable engagement with the adjacent corresponding break-bar-supporting member 17, and has a plurality of horizontally elongated slots disposed longitudinally of the machine frame and in superposed relation to each other in each of said angular end portions 20. And each of said slots 21 has a securing screw or bolt 22 extending horizontally therethrough, each of said bolts or screws being anchored in the corresponding adjacent vertically adjustable bar-supporting member 17. By providing each of the vertically adjustable bar-supporting members 17 with suitable teeth or serrations, or shoulders 23 in superposed relation to each other, and providing a tooth-engaging shoulder or teeth 24 upon an adjacent stationary part, such, for instance, as the stationary supporting member upon which such vertically adjustable member 17 is mounted, the members 17 may be rigidly secured in any desired adjusted position, so as to form a strong and rigid support for the break bars in any desired position to which the latter are adapted to be moved or adjusted. (See Fig. 1.)

Mounted forward of the break-bars 12 and 13 is a pair of initial feeding rollers 25, 26 which are arranged in horizontal position and in superposed parallel relation to each other and transversely with respect to the machine frame, the bottom of the upper roller 26 being, by preference, normally below the level of the bottom fiber engaging or stalk-breaking edge or margin 15 or lower rear edge of the upper break-bar 12, and as high as is necessary to permit stalks of fibrous material to be fed between said roller and between and in position to be engaged and broken by or against the stalk-breaking margins or edges 15 and 16 of said break-bars, with the stalks, by preference, in approximately horizontal position or in perpendicular relation to an imaginary line drawn from the stalk-breaking margin 15 to the stalk-breaking margin or edge 16 of the break-bars, between which the stalks are to be fed transversely with respect to the break bars.

The feeding rollers 25, 26 are, by preference, made of flexible material, such as rubber, or a composition containing flexible material, or of resilient material such as spring metal, the body portions of said rollers being mounted upon suitable axles 27, 28 which are journaled in suitable bearings in the main frame.

The axle of the bottom roller 26 is shown mounted in suitable bearings in the form of

bearing blocks 29, one of said blocks being mounted in a vertical slot—not shown—in the side frame member 4 and the other of said blocks being mounted in the bottom of 5 a similar vertically elongated slot 31 in the opposite side frame member 8. The axle of the upper feed roller 25 is journaled in vertically slidable bearing blocks 32, 32 located directly over the corresponding bearing blocks 29, one of the bearing blocks 32 being slidably mounted in the slot 30 in the upright frame member 4 and the other in the slot 31 in the upright frame member 8. Each of the bearing blocks 32 is provided 10 with a compression spring 33 interposed between such bearing block and a washer 34, and with a pressure-regulating screw 35 in operative engagement with the washer and in threaded engagement with a plate or frame member 36, for regulating the tension of the corresponding spring. The bearing blocks 32 are thus yieldingly supported in position, so as to permit the upper feeding roller 25 to be pressed upward against the 15 tension of the springs 33 by stalks of fibrous material as the latter are fed endwise between and transversely with respect to the rollers and between the break-bars. The rollers 25 and 26 are provided with spur 20 gears 36, 37, the gear 36 being in fixed relation to the upper roller and the gear 37 being fixed to the axle of the lower roller 26. These gears have elongated teeth adapted to 25 permit the rollers to be spread apart to the desired extent by stalks of fibrous material 30 passing between the rollers in layers which vary more or less in thickness. The lower feed roller is connected with a suitable 35 source of power by means of a sprocket 38 fixed to the shaft or axle 28 of said 40 roller, a sprocket wheel or gear 39 fixed to a main driving shaft 40 which extends transversely of and is journaled in suitable bearings 41 in the main frame, and a sprocket 45 chain or equivalent element 42 in engagement with the toothed sprocket wheels 38 and 39, and forming a connection between the same. The main driving shaft 40 is provided with a driving wheel or belt pulley 50 43 by means of which it is connected with a suitable source of power, such as an engine or motor,—not shown. A feed table 44 is mounted in position to support stalks or 55 hemp or fibrous material in a suitable manner to permit the stalks to be fed between the feed rollers 25 and 26 and between the break-bars 12 and 13, or into position to extend it transversely across the break-bar mechanism.

60 The upper feed-roller 25 is provided with a flexible scraper 46 interposed between said roller and the adjacent break-bar 12; and the lower feed-roller 26 is provided with a similar scraper 47, arranged in relatively inverted position directly beneath the scraper 46 and between the lower roller 26 and the lower break-bar 13. These scrapers are supported at their opposite ends by suitable means adapted to permit the scrapers to be held in yielding frictional engagement with the rollers, and to permit the upper scraper to move with the upper roller 25 as the latter is raised or lowered with respect to the lower roller. This may be accomplished in the manner shown in the drawings, by providing bell cranks 48 which are fixed to the opposite ends of the upper scraper 46, and pivotally supported by means of pivots 49, 49 which are anchored in suitable stationary supports, such, for instance, as the frame 70 members 4 and 8, respectively. Springs 50 attached to the free ends of the bell cranks 48, and with one end attached to a stationary part of the frame, serve to yieldingly hold the scrapers 46 in yielding engagement with 75 the roller 25. The scraper 47, which engages the lower roller 26 is provided with similar bell cranks 51 attached to its opposite ends and each pivotally supported by means of a pivot 52 anchored in an adjacent stationary 80 part of the main frame, and each bell crank 51 is provided with a spring 53 connected therewith and with the stationary main frame.

85 The scrapers above described serve to 90 prevent the fibrous material from wrapping around the feed rollers.

95 Mounted directly back of and in substantially parallel relation to the lower break-bar 13 in position to co-act with the upper break-bar 12 and break and loosen shives or

100 haulds of stalks extending transversely across and beneath the stalk-breaking edge 15 of said upper break-bar, is a set or series of pivoted non-invertible beater-bars 54 each of 105 which is pivotally connected at one end with a disk-shaped rotator or wheel 55, and at its opposite end, with a somewhat similar disk-shaped rotator or wheel 56, said beater-bar supporting wheels or disks being located 110 near the opposite extremities of the break-bars and rotatively supported by means of parallel shafts or axles 57 and 58, respectively, in position to enable the beater-bars above mentioned to be operated in such a 115 manner that each of the beater-bars is caused to travel in a circuit or path oblique to itself, all of said beater-bars being constantly in parallel relation to each other and in substantially parallel relation to the breaker-bar 12, and the supporting shafts 57 and 58 being in parallel relation to each other but in oblique relation to the beater-bars 54 and also in oblique relation to the parallel pivoted non-invertible beater-bars operated by 120 said shafts. These pivoted non-invertible beater-bars 54 are each pivotally connected with the rotator or beater-bar supporting wheel 55 by means of a pivot—not shown—

125 fixed to or integral with the beater-bar. 130

The axes of these pivots are parallel to the shaft 57 and perpendicular to the face of the disk or beater-bar supporting wheel 55. The face of said beater-bar supporting wheel 55, in engagement with which the pivoted ends of the beater bars are mounted, is in perpendicular or right-angular relation to the axis of the shaft 57, and in parallel relation to the beater-bar-engaging face of the beater-bar supporting wheel 56, with which the opposite ends of each of said beater-bars is connected by means of a pivot pin 60 which is fixed to or formed integral with the beater-bar supported thereby. The pivots 60 are securely held in place in their bearings in the wheel 56 by means of suitable retaining nuts or collars 61 fixed to the ends of said pivots on the opposite side of the wheel from that engaged by the pivoted ends of the beater-bars; and the pivots 59 at the opposite ends of the beater-bars are securely held in place in their bearings in the wheel or disk 55 by retaining collars or nuts—not shown—which may be of the same form as the retaining collars 61. The retaining plate or collars 61 are, by preference, so constructed as to enable the pivots to be provided with suitable ball bearings, comprising antifriction balls—not shown—arranged in position to encircle the pivots and afford suitable bearings for the same. The ball bearings or antifriction bearings may be of any desired ordinary and well known form suitable for the purpose indicated, and it is therefore not deemed necessary or desirable to describe the same in greater detail.

The beater-bars 54 are, by preference, each so constructed as to comprise two relatively movable beater-bar members, namely, the main body portion to the opposite end portions 64 of which the pivots are attached, for pivotally connecting said main body portions or beater-bars proper with the beater-bar supporting wheel and a shoe or fiber-engaging outer bar member 65 which is mounted upon and in longitudinally movable relation to such main body portion. These shoe members 65 are by preference of angular construction, or in the form of an inverted "U" in cross-section, with the upper margin flattened so as to provide a fiber-engaging striking edge or margin 66 adapted to extend transversely across stalks of fibrous material which extend transversely across and beneath the bottom fiber-engaging edge 15 of the upper break-bar 12 in position to be broken and scutched while being fed lengthwise of the stalks between the break bars and beater bars.

Each of the shoes 65 is provided with a projecting stud 71 thereon; and a detent or tripping member 72 is mounted in position to successively engage and retard and interrupt the movement of the bosses 71 and the beater-bar shoes to which they are at-

tached, at the moment when the shoes are moving into and actually in breaking contact with the stalks as the latter are passing lengthwise of the stalks between the fiber-engaging edge of a break bar and the corresponding shoes or beater bars.

Mounted directly back of and in substantially parallel relation to the upper break-bar 12, and in parallel relation to and in position to co-act with the lower break-bar 13 and with the lower rotative beater-bars 65 above described, to break and scutch the stalks of hemp or other fibrous material fed into position to extend between said break-bars 13, is an upper set or series of 80 pivoted non-invertible beater-bars 77, each of which is pivotally connected at one end with a beater-bar supporting rotator or disk-shaped wheel 78, and at the other end, with a disk-shaped beater-bar supporting 85 rotator or wheel 79, said wheel 78 being fixed to a rotative shaft 80, and said wheel 79 being fixed to the end of a rotative shaft or axle 81, said shafts 80 and 81 being in parallel relation to each other and in oblique 90 relation to the beater-bars 77 and break-bar 13. The shaft 80 is in the same vertical plane with the shaft 58 already described, and the shaft 81 is likewise, by preference, directly over and in the same vertical plane 95 but at an angle with respect to the shaft 57 already described,—the beater-bars 77 and 65 being normally horizontal and in parallel relation. The main body of each beater-bar 77 is provided at one end with 100 a pivot 82 fixed thereto and mounted in a bearing or aperture in the wheel 78, and at the other end, with a similar pivot 83 mounted in a suitable bearing in an aperture in the wheel 79, the pivots 82 having 105 their longitudinal centers parallel with the axis of the shaft 80, and the pivots 83 having their axial centers parallel with the axis of the shaft 81. The shaft 80 is rotatively mounted in a suitable bearing 84 110 upon or forming part of the main frame of the machine; and the shaft 81 is rotatively mounted in a similarly inclined bearing 85 on or forming part of the opposite side of the main frame. (See Figs. 1, 2 and 3.) 115

Mounted upon and in longitudinally slid-
able relation to each upper beater-bar mem-
ber 77 is an outer shoe member 86 which
is held in position upon and in longi-
tudinally slidable relation to such beater-bar 120
member 77 by means of laterally projecting
retaining pins or bosses 87, which project
into and in sliding engagement with the
walls of longitudinally elongated slots 88,
which are adapted to permit the movement 125
of the shoes longitudinally with respect to
the main beater-bar members 77. Each of
the upper beater-bars is provided at one
end with a tension spring 89 which is con-
nected at one end with the shoe member 86 130

and at the opposite end of said spring with the enlarged end portion of the main body portion of such beater bar; and the opposite end of each of said upper beater-bars is 5 provided with a compression spring 90, one end of which is connected with said end of the beater-bar shoe 86, and the other end of which is connected with the enlarged adjacent end portion 91 of the main body portion of such upper beater-bar. Each upper beater-bar shoe member 86 is provided with a laterally projecting boss or stud 92, which corresponds with the bosses 71 on the lower beater-bar shoe members already described, 10 and is adapted to engage and to be released from engagement with a tripping member or detent 93 which is secured in position on the upper break-bar 12, so as to trip and release the bosses 92 and thereby retard and 15 interrupt the movement of the upper beater-bar shoe members 86 in the same manner in which the detent 72 retards, interrupts and releases the bosses 71 and the lower beater-bar shoe members 65 already described.

20 The upper beater bars 77 are securely held in pivotal relation to the rotators or beater-bar supporting wheels 78 and 79 by means of pivot pins 82 and 23 already described, the pivot pins 82 being provided with retaining collars or nuts 97 fixed thereto in position to engage the back of the wheel 78, and the pins 83, having collars of the same construction—not shown—fixed to the back end thereof and adapted to engage the back 25 face of the wheel 79 in like manner. The shaft 80 is provided at its upper forward end with a retaining collar 98 fixed thereto and adapted to engage the bearing 84, so as to hold the shaft in place in its bearing; 30 and the shaft 81 is provided at its rear lower end with a similar retaining collar 99 fixed thereto and adapted to engage the bearing 85 so as to hold said shaft in operative position in its bearing. (See Figs. 1 and 2.)

35 The driving mechanism for operatively connecting and driving the upper and lower sets of pivoted beater-bars and their rotators or beater-bar supporting wheels, is constructed as follows: Mounted upon and 40 in fixed relation to the lower beater-bar supporting wheel or rotator 56 is a toothed bevel gear or gear ring member 100, which is thus operatively connected in fixed relation to the shaft 58, already described, 45 said shaft being rotatively mounted in a suitable bearing 101 in the main frame. (See Figs. 1 and 2.) Mounted upon and in fixed relation to the upper beater-bar supporting wheel 78, and thereby operatively 50 connected with the shaft 80, and in toothed engagement with the beveled toothed gear 100, is a toothed bevel gear ring or wheel 102, which is of identical construction and dimensions with said gear member 100. Said gears are therefore adapted to have the 55 same speed of rotation. A toothed bevel gear member 103 is mounted in fixed concentric relation to the lower beater-bar supporting wheel 55 already described, and is thus operatively connected with and in fixed 60 relation to the shaft 57 already described, said shaft being rotatively mounted in a suitable inclined bearing 104 in the main frame and directly beneath and in the same perpendicular plane with the shaft 81 65 already described. (See Figs. 1, 2 and 3.) Mounted upon fixed relation to the upper beater-bar supporting wheel 79 already described, and in fixed concentric relation to the shaft 81 is a toothed bevel gear wheel 70 or member 105 which is in toothed engagement with the bevel gear wheel 103. Said beveled gear wheels 103 and 105 are of the same construction and dimensions, and are therefore adapted to have the same speed 75 of rotation, their speed of rotation being the same as that of the wheels 100 and 102 already described. (See Figs. 1, and 3.)

77 The shaft 58 and its beater-bar supporting wheel 56 are operatively connected with 80 the main driving shaft 40, already described, by means of a shaft 106 rotatively mounted in a bearing 107 in the main frame, a toothed bevel gear wheel 108 fixed to the shaft 58 and in toothed engagement with a 85 similar bevel gear wheel 109 fixed to the shaft 106, a toothed bevel gear wheel 110 fixed to the opposite end of the shaft 106, and in toothed engagement with a toothed bevel gear wheel 111 which is fixed to the 90 main driving shaft 40. (See Figs. 1, and 3.)

95 The shaft 57 and its beater-bar supporting wheel 55 and gear 103 are operatively connected with the main driving shaft 40, 105 or source of power, by means of a shaft 112 which is rotatively mounted in a bearing 113 in the main frame, a toothed bevel gear wheel 114 fixed to the end of the shaft 57 and adapted to hold said shaft against 110 endwise movement in its bearing, said gear wheel 114 being in toothed engagement with a toothed bevel gear wheel 115 fixed to one end of the shaft 112, a toothed bevel gear wheel 116 fixed to the opposite end of the 115 shaft 112, and a toothed bevel gear wheel 117 fixed to the main driving shaft 40 and in toothed engagement with the gear 116.

120 The pivoted beater bars located above the level of the top fiber-engaging edge of the 120 lower break bar are thus adapted to be rotated or driven in a circuit which is oblique to the longitudinal centers of said beater bars, and are caused to move downward past the fiber engaging upper edge of said 125 lower break-bar in such a manner as to engage the upper side of the stalks or layer of hemp or fibrous material to be operated upon, so as to break the shives or hurds and loosen them from the fibers, and so as to 130

have a scutching movement in a direction longitudinally of the stalks, such scutching movement being an uninterrupted continuation of the movement by means of which the 5 breaking was effected, but in a direction away from the fiber engaging edge of the lower break-bar and with the upper pivoted beater bars in such relation to the lower beater-bars as to come between the latter 10 in successive order, and in such a manner that the upper and lower beater bars are caused to pass longitudinally along and in scutching engagement with opposite or top and bottom sides of the fibrous material 15 simultaneously while the stalks are being fed endwise between and transversely with respect to the upper and lower break-bars and between the upper and lower sets of pivoted beater-bars. By setting the beater-bar 20 supporting wheels and their supporting shafts at the proper oblique angle with respect to the longitudinal centers of the beater-bars and with respect to the break bars, the length and extent of the scutching movement of the rotative beater-bars 25 may be caused to be in just the right proportion to the speed and force of the striking movement, so that the fibrous material will be properly scutched and cleaned without unnecessary breaking or injury of the 30 fibers.

In order to provide simple and efficient means for removing such shives or hurds from the fibers as may remain in the material passing from between the pivoted beater-bars, I provide a rotary beater mechanism which is located rearward with respect to the pivoted beater-bars already described, and which comprises in its construction a 35 drum or frame which is by preference of cylindrical form consisting of a pair of opposite end rings or drum heads 118, 118 fixed to a shaft 119 which is journaled at its opposite extremities in suitable bearings 120, 40 120 in the main frame, said shaft being operatively connected with the main driving shaft 40, already described, by means of a sprocket wheel 121 fixed to the main driving shaft, a similar toothed sprocket wheel 50 122 fixed to the shaft 119, and a sprocket chain 123 mounted upon and forming a connection between said sprocket wheels. The end rings or drum head members 118 of the drum or cylindrical frame on the shaft 119 55 are rigidly connected by means of suitable longitudinal peripheral connecting members or ribs 124, the opposite ends of which are rigidly mounted in said rings or heads and adapted to form a strong, comparatively 60 light, and rigid frame. These ribs may be in the form of peripheral rods having their opposite ends inserted into and riveted or otherwise firmly connected with the rings.

A multiplicity of peripheral flail-like circumferentially disposed beater blades or

arms 125 are pivotally mounted in staggered relation to each other upon the periphery of the drum 126, with which they are pivotally connected by means of a plurality of longitudinal peripheral rock-shafts 127, the opposite ends of which are rotatively mounted in suitable bearings in the end rings or drum head members 118.

A plurality of these circumferential flail-like blades are fixed to each of these rock 75 shafts 127 so as to rock or swing outward and inward as the shafts are rocked or partially rotated upon their axes during the rotation of the drum upon its axis, which is parallel with the axes of the rock shafts 80 each of which thus forms a rocking axle for its set or series of flail-like blades or arms 125. The leading ends of the blades 125 being thus pivotally connected with the drum, and the blades being so arranged that each 85 extends rearward with respect to the direction of movement of the periphery of the drum and of the blades, it is plain that the action of centrifugal force will tend to cause the free rearward ends of the blades to 90 swing outward circumferentially, as the drum with its peripheral blades or arms, is rotated, the normal direction of rotation being such that the upper half of the drum or frame moves rearward and carries the 95 flail-like arms therewith. In order to provide means for positively rocking the flail-like blades and the rock shafts with which they are connected, in such a manner as to cause the blades, during their upward and 100 rearward movement, to strike and pass upward and rearward in scutching engagement with and be between the fibers in the layers of fibrous material passing from the rotative longitudinal beater-bars already described, 105 so as to separate the fibers and remove the shives or hurds therefrom, each of the rock-shafts 127 is provided with one or more crank arms 128 fixed thereto, I prefer to employ one crank arm to each end of each rock 110 shaft, each crank arm having a crank pin 129 at its out extremity in position to extend into and in operative engagement with an adjacent cam 130, having a continuous cam groove 131 which is in eccentric relation to 115 the axis of the drum, the circumferential walls of said cam groove being of such form as to operatively engage the crank pins, which may be provided with anti-friction sleeves or rollers 132 encircling the crank 120 pins and rotatively supported between and in engagement with the walls of the cam slot, so that the pivoted blades supported by the rock shafts will move outward circumferentially and upward during the upward and rearward movement of the rock 125 shafts with which they are connected, and inward immediately preceding the beginning of such upward and outward movement of the blades on their axes formed by 130

the rock shafts with which they are connected.

Although more or less satisfactory results may be accomplished with a machine having but one cam, and one set of crank arms to be operated by means of such cam, I prefer to employ two fixed cams, one at each end of the drum, and each in position to operatively engage and operate an adjacent crank 10 arm secured to the corresponding ends of the rock shafts. The flail-like blades or flail arms are so disposed that those on any given rock shaft are in staggered relation to those on the next adjacent rock shafts, throughout out the entire circumference of the drum or rotary flail-arm supporting frame.

Mounted in position to extend over and rearward with respect to the drum and the flail-arms thereon, is a series of stationary 20 curved ribs 133, each of which partially encircles the drum or rotative flail-arm supporting frame in such a position that the pivoted flail-arms 125 will extend across the space between said ribs and the periphery 25 of the drum in position to pass between the ribs during the movement of the flail-arms rearward upon the rearwardly moving upper half of the drum. There is a sufficient number of these curved stationary ribs so 30 that each of the flail-arms is enabled to pass between a pair of such ribs while in engagement with and in position to pass between and longitudinally of the fibers passing over the flail mechanism and between the periphery of the flail-arm supporting frame or 35 drum and said ribs.

An endless conveyor belt 134, which is provided with a multiplicity of fiber-engaging bosses or studs 135 thereon, is arranged 40 horizontally at the rear or discharge side of the rotary flail-arm mechanism, in position to receive and carry away the fibrous material cleaned by the mechanism above described. This conveyor belt may be supported by means of ordinary cylindrical rollers 135', only one of which is shown. (See Fig. 3.) The belt-supporting roller 135' shown in Fig. 3, is supported upon a shaft 136 which is journaled in suitable bearings 50 in the frame. A feed roller 137 is rotatively mounted over and in engagement with the top side of the feed belt and in parallel relation to the roller 135', and supported by means of an idler shaft 138 the opposite 55 ends of which are journaled in suitable bearings 139 in the machine frame. A concave scutching shield or scutching concave 140 is provided and mounted in position to extend downward and forward in front of the forward extremity of the carrier apron 134, being supported in operative position by 60 means of suitable side brackets 141. This scutching concave has its forward concave surface in position to support the last extremities of the fibers to pass into position

to be carried across said scutching concave and onto the carrier belt 134, in such a manner that the flail-arms will strike and clean the fibers while they are held by the apron 134 and roller 137 and caused to pass over 70 and across said scutching concave in position to be engaged and scutched and cleaned by the flail arms as they pass in close proximity to the scutching concave.

A lower main conveyor belt or apron 142 75 is mounted in position to extend beneath the fiber-treating mechanism above described, and from a point directly below the break-bars to and beyond the rear extremity of the machine, said belt being mounted at its 80 forward extremity upon a driving roller 143 fixed to a supporting shaft 144. A helical conveyor 145, is mounted in a discharge chute 146 which is located at the rear extremities of the parallel longitudinally extending curved ribs 133 in position to extend transversely across the machine and receive the hauls or shives and to and waste material thrown out between said ribs by the action of the flail-arms. This conveyor may 90 be of any desired ordinary or suitable form, but when constructed as shown in the drawings, consists of a rod bent into the helical form of a cork-screw having an end axle portion 147 which may be made in one integral 95 piece with the helical part of the conveyor, and journaled in a suitable bearing 148 in the machine frame. This conveyor is adapted to rotate in a direction necessary to discharge material from the end of the chute 100 opposite to that at which the axle is located, and is operatively connected with the shaft 119, already described, by means of a sprocket wheel 149 on the axle 147, a sprocket wheel 150 fixed to the shaft 119, and a 105 sprocket chain 151 mounted upon and connecting said sprocket wheels. The driving shaft 136, for driving the carrier belt 134 is operatively connected with the axle 147 of the carrier 145, by means of a sprocket 110 wheel 152 on the shaft 136, a sprocket wheel 153 on the axle 147 and a sprocket chain 154 mounted upon and connecting said sprockets. The ribs 133 and chute 146 are covered 115 and enclosed by means of a sheet metal casting 155, the rear extremity of which is connected with the chute, and the forward extremity of which extends to or forward beyond the forward extremities of said ribs, and is supported by a transverse frame-member 156 which also serves to support the forward ends of the series of ribs 133, and to brace and strengthen the machine frame.

An upper intermediate feed roller 157 and a lower intermediate feed roller 158 may be 125 interposed between the rotative beater-bar mechanism comprising upper beater-bars 77 and lower beater bars 54, and the rotative drum and flail-arm mechanism, said intermediate feed rollers being suitable for re- 130

ceiving the fibrous material passing from said rotative beater-bar mechanism to said drum and flail-arm mechanism, to prevent the fibrous material from being released too soon or before being caught and properly held and fed rearward by the rear carrier apron 134 and roller 137. The bottom roller 158 is fixed to a shaft 159 which is journaled in suitable bearings 160 in the machine frame; and the upper roller 157 is fixed to a shaft 161 journaled at its opposite ends in sliding bearing blocks 162 which are mounted in slidable engagement with and in position to move upward and downward between upright ways 163, on opposite sides of the machine frame. Compression springs 164 in engagement with the upper sides of said bearing blocks, and held at the desired tension by means of tension screws 165 in threaded engagement with screw-supporting and retaining plates 166 serve to yieldingly hold the bearing blocks in position and permit the upward movement of the upper roller 157 toward and from the lower roller 155 as the condition of the fibrous material may require. In practice I find it desirable to have the last mentioned rollers sufficiently loosely in engagement with the fibrous material to prevent the material from being subjected to strains such as will injure or break the fibers to any avoidable extent during the operation of cleaning the same. The rollers 157 and 158 are operatively connected so as to rotate in unison, by means of spur gear wheels 167 and 168, the spur gear 167 being fixed to the shaft 159 of the lower roller, and the spur gear 168 being fixed to the shaft 161 of the upper roller, and in toothed engagement with the gear 40 167.

The shaft 159 of the roller 158 is operatively connected with the shaft 119, so as to be driven by the latter, by means of a sprocket wheel 169 fixed to the shaft 159, a sprocket wheel 170 fixed to the shaft 119, and a sprocket chain 171 mounted upon and connecting said sprockets. The shaft 144 of the roller 143 which supports the forward extremity of the discharge conveyor 50 142, is operatively connected with the drive shaft 40 by means of a sprocket wheel 172 fixed to the shaft 144, a sprocket wheel 173 fixed to the shaft 40, and a sprocket chain 174 mounted upon and connecting said sprocket 55 wheels.

By providing each of the pivoted flail-like arms 125 with lateral ribs or serrations 175 on each side of each of said arms and in position to engage the fibrous material 60 through which the said flail arms are caused to pass, shives or hurds which have been broken and loosened or partially loosened from the fibers will be dislodged from engagement with the fibers and thrown out 65 from between them and between the spaced curved or concave scutching ribs 133 and into the chute 146 to be carried away by the screw conveyor 145, or other suitable discharge device. The ribs 133 are so constructed and spaced apart as to extend 70 partly around the drum or rotative beater-arm-supporting frame adjacent to the periphery of the latter and in position to prevent the fibrous material operated upon from passing out between said ribs, but to permit 75 the shives or hurds and some tow or short fibers and waste material to pass out between the ribs and into the discharge chute 146. The fibers passing along between the ribs 133 and the flail-like beater arms 125, however, are flexed by the latter and caused to move rearward in contact with the ribs 133 and between said ribs and in contact with the flail-like arms, until the fibrous material is caught up by the rear carrier belt 134, and 80 still further scutched and cleaned between the flail-like beater arms 125 and the scutching concave 140 which is arranged adjacent to the periphery of the flail-arm-supporting drum or frame 126 and extends from end to 85 end of the same. (See Figs. 1 and 3.)

From the foregoing description it is plain that a machine having only one break-bar used in connection with one co-acting series of pivoted beater-bars, or with two series of 95 co-acting pivoted beater-bars adapted to admit stalks between the adjacent stalk-breaking edge of such stationary break-bar and the pivoted beater-bars in such a manner as to cause the stalks to be broken and 100 scutched by the pivoted beater-bars, and between such stationary break-bar and the co-acting pivoted beater bars, will operate with more or less satisfactory results; but that, by employing two series of pivoted beater-bars adapted to admit stalks therebetween the stalks are engaged on opposite sides, and may be in simultaneous engagement with one or more pivoted beater bars of both 110 series, the beater-bars coming into contact with the fibrous material on opposite sides of the same alternately and in such a manner as to cause the fibrous material to be broken against the upper and lower break-bars alternately, in case a plurality of stationary break-bars are employed. It is also plain that the rear rotative beater mechanism consisting of the flail-arms and their rotative supporting frame or drum, and the 115 curved stationary scutching ribs arranged 120 adjacent to and in position to co-act with the flail-arms, are adapted to be used in connection with any suitable means for breaking or breaking and scutching the stalks or 125 fibrous material prior to subjecting the material to the action of said last mentioned beater mechanism; but that very desirable results and advantages accompany the use of pivoted or movable beater arms arranged in substantially parallel relation to each 130

other and adapted to extend transversely with respect to the path of movement of the fibrous material to be operated upon in combination with rotative beater mechanism 5 comprising a series of flail-like pivoted beater-arms pivotally connected with the periphery of a rotative supporting frame or drum and having a movement in a direction parallel with or in the same direction with 10 the path of movement of the fibrous material to be operated upon, or at an angle to the longitudinal centers of the parallel pivoted non-invertible beater-bars.

I claim:

- 15 1. In a machine of the class described, the combination of a rotative beater-supporting frame, a series of beater arms each having pivotal connection with said rotative supporting frame, the axes of said pivoted beater arms being in substantially parallel relation to the axis of said supporting frame, a scutching member mounted adjacent to said rotative beater-arm supporting frame and adapted to admit fibrous material be- 20 tween the pivoted beater arms and said scutching member, to be scutched and cleaned, stalk-breaking mechanism, for breaking stalks of fibrous material to be scutched and cleaned between said beater arms and said 25 adjacent scutching member, means for feeding stalks into position to be operated upon by said beater arms, and means for operating said stalk breaking mechanism and said rotative beater-arm supporting frame.
- 30 2. In a machine for treating fibrous material, the combination of a rotative beater-arm-supporting frame mounted in suitable bearings, a series of beater-arms each having its leading end pivotally connected with 35 the peripheral portion of said rotative supporting frame, the axes of said pivoted arms being in substantially parallel relation to the axis of the rotative supporting frame, the main body of each of said pivoted arms 40 being arranged in position to extend outward from its axis and backward with respect to the direction of rotation of said rotative supporting frame, a series of stationary scutching ribs mounted adjacent to said 45 pivoted beater-arms and adapted to admit fibrous material between the pivoted beater-arms and said ribs, to be scutched by the beater-arms, said ribs being spaced apart and adapted to permit waste material to 50 pass therebetween as such waste material is separated from the fibrous material passing between the pivoted beater-arms and the adjacent inner edges of said ribs, and means for operating the rotative beater-arm-sup- 55 porting frame.
- 55 3. In a machine for treating fibrous material, the combination of a rotative beater-arm-supporting frame mounted in suitable bearings, a series of beater-arms each hav- 60 ing its leading end pivotally connected with 65
- the peripheral portion of said rotative supporting frame, the main body of each of said pivoted arms being arranged in position to extend outward from its axis and backward with respect to the direction of 70 rotation of said rotative supporting frame, a series of stationary scutching ribs each mounted adjacent to and in position to extend circumferentially with respect to the rotative beater-arm-supporting frame, and 75 adapted to permit the passage of fibrous material between said beater-arms and said stationary ribs, to be scutched by the beater-arms, said ribs being spaced apart, to permit the passage of waste material therebetween, means for feeding fibrous material into position to pass between the pivoted beater-arms and the adjacent stationary ribs, to be scutched by the beater-arms, and means for rotating said beater-arm-supporting frame.
- 80 4. In a machine for treating fibrous material, the combination of a rotative beater-arm-supporting frame mounted in suitable bearing, a series of beater-arms each hav- 85 ing its leading end pivotally connected with the peripheral portion of said rotative supporting frame, the main body of each of said pivoted beater-arms being arranged in position to extend outward from its axis and backward at an angle with respect to the direction of rotation of such beater-arms and rotative supporting frame, a series of 90 stationary scutching ribs each mounted adjacent to and in position to extend circumferentially with respect to said rotative supporting frame, and adapted to permit the passage of fibrous material between said beater-arms and said stationary ribs, to be scutched by the beater-arms, said ribs being spaced apart and adapted to permit the passage of waste material therebetween, and having inner fiber-engaging edges adapted to guide fibrous material along the inner sides of 95 said ribs, and in position to be engaged by said pivoted beater-arms, means for rocking the pivoted beater arms upon their axes with respect to the rotative beater-arm-sup- 100 porting frame, and means for rotating said beater-arm-supporting frame.
- 105 5. In a machine for treating fibrous material, the combination of a rotative beater-arm-supporting frame mounted in suitable bearings, a series of beater-arms each hav- 110 ing its leading end pivotally connected with the peripheral portion of said rotative supporting frame, a series of stationary scutching ribs mounted adjacent to said pivoted beater-arms and adapted to admit fibrous material between the pivoted beater-arms and said ribs, to be scutched by the beater-arms, said ribs being spaced apart and adapted to permit waste material separated from fibrous material to pass outward between said stationary ribs, a discharge re- 115
- 120
- 125
- 130

- ceptacle arranged in position to receive waste material permitted to pass outward between said stationary ribs, means for permitting the passage of fibrous material 5 from between the pivoted beater-arm mechanism and said stationary scutching ribs as such fibrous material is separated from the waste material, means for feeding material to be operated upon into position to pass between said pivoted beater-arms and said stationary scutching ribs, and means for operating the rotative beater-arm-supporting frame.
6. In a machine for treating fibrous material, the combination of a rotative beater-arm-supporting frame mounted in suitable bearings, a series of beater-arms each having its leading end pivotally connected with the pivotal portion of said rotative supporting frame, the main body of each of said pivoted beater-arms being arranged in position to extend outward from its axis and backward at an angle with respect to the direction of rotation of such beater-arms 25 and rotative supporting frame, a series of stationary scutching ribs each mounted adjacent to and in position to extend circumferentially with respect to said rotative supporting frame, and adapted to permit the passage of fibrous material between said beater arms and said stationary ribs, to be scutched by the beater-arms, said ribs being spaced apart and adapted to permit the passage of waste material therebetween, and 30 having inner fiber-engaging edges adapted to engage and guide fibrous material along the inner sides of said ribs and in position to be engaged by said pivoted beater-arms, means for feeding material to be operated upon in position to pass between the pivoted beater-arms and the adjacent stationary ribs, means for rocking the beater-arms upon their axes, and means for operating the rotative beater-arm-supporting frame.
- 45 7. In a machine for treating fibrous material, the combination of a rotative beater-arm-supporting frame mounted in suitable bearings, a series of peripheral rock-shafts each rockingly mounted in said rotative frame and in substantially parallel relation to the axis of the latter, a beater-arm fixed to each of said rock-shafts, the main body of each of said beater-arms being arranged in position to extend outward from the axis 50 of the rock-shaft with which it is connected and backward with respect to the direction of rotation of the beater-arms and said rotative supporting frame, means for rocking the rock-shafts upon their axes, means for feeding fibrous material into position to be operated upon by said beater-arms, and means for operating the rotative beater-arm-supporting frame.
- 60 8. In a machine for treating fibrous material, the combination of a rotative beater- 130 arm-supporting frame mounted in suitable bearings, a series of peripheral rock-shafts each rockingly mounted upon said rotative frame and in substantially parallel relation to the axis of said frame, a plurality of 70 beater-arms fixed to each of said rock-shafts, the main body of each of said beater-arms being arranged in position to extend outward from the rock-shaft with which it is connected and backward with respect to the 75 direction of rotation of the beater-arms and said rotative supporting frame, means for rocking the rock-shafts upon their axes, a concave scutching member mounted in position to admit material to be operated upon 80 between said concave scutching member and the pivoted beater-arms of said rock-shafts, and means for operating the rotative beater-arm-supporting frame.
9. In a machine for treating fibrous material, the combination of a rotative beater-arm-supporting frame mounted in suitable bearings, a series of peripheral rock-shafts each rockingly mounted in said frame and in substantially parallel relation to the axis 85 of the same, a plurality of peripheral beater-arms fixed to each of said rock-shafts, the main body of each of said beater-arms being arranged in position to extend outward from the rock-shaft with which it is connected and 90 backward with respect to the direction of rotation of the beater-arms and said rotative supporting frame, a series of stationary scutching ribs mounted adjacent to said beater-arms and adapted to permit the passage of material to 100 be operated between said beater-arms and said stationary scutching ribs, said scutching ribs being spaced apart and adapted to permit the passage of waste material therebetween, and having inner fiber-engaging 105 edges adapted to engage and guide fibrous material along the inner surfaces of said ribs and in position to be engaged by said beater-arms, means for rocking the rock-shafts upon their axes, and means for rotating the rotative beater-arm-supporting frame.
- 110 10. In a machine for treating fibrous material, the combination of a rotative beater-arm-supporting frame mounted in suitable 115 bearings, a series of peripheral rock-shafts each rockingly mounted in said rotative frame and in substantially parallel relation to the axis of the same, a beater-arm fixed to each of said rock-shafts, the main body 120 of each of said beater-arms being arranged in position to extend outward from the axis of the rock-shaft with which it is connected and backward with respect to the direction of rotation of the beater-arms and said rotative supporting frame, crank and cam mechanism operatively connected with the rock-shafts, for rocking the same upon their axes, 125 means for supporting fibrous material in position to be engaged and scutched by said 130

beater-arms, and means for rotating the rotative supporting frame.

11. In a machine for treating fibrous material, the combination of a rotative beater-arm-supporting frame mounted in suitable bearings, a series of peripheral rock-shafts each rockingly mounted in said rotative frame and in substantially parallel relation to the axis of the same, beater-arms fixed to said rock-shafts, the main body of each of said beater-arms being arranged in position to extend outward from the axis of the rock-shaft with which it is connected and backward with respect to the direction of rotation of the beater-arms and said rotative supporting frame, a crank fixed to each rock-shaft, respectively, a stationary cam in operative engagement with said crank mechanism, for rocking the rock-shafts, means for supporting fibrous material in position to be engaged and scutched by said beater-arms, and means for rotating said rotative supporting frame.
12. In a machine for treating fibrous material, the combination of a rotative beater-arm-supporting frame mounted in suitable bearings, a series of peripheral rock-shafts each rockingly mounted in said rotative supporting frame and in substantially parallel relation to the axis of the same, beater-arms fixed to said rock-shafts, the main body of each of said beater-arms being arranged in position to extend outward from the axis of the rock-shaft with which it is connected and backward with respect to the direction of rotation of the beater-arms and said rotative supporting frame, a crank fixed to each rock-shaft, a stationary cam mounted upon a suitable support and in operative engagement with said crank mechanism, for rocking the rock-shafts, means for supporting fibrous material in position to be engaged and scutched by said beater-arms, feeding means adapted to feed fibrous material into position to pass between said fiber-supporting means and said beater-arms, and means for rotating the rotative supporting frame.
13. In a machine for treating fibrous material, the combination of a rotative beater-arm-supporting frame mounted in suitable bearings, a series of peripheral rock-shafts each rockingly mounted in said rotative supporting frame and in substantially parallel relation to the axis of the same, beater-arms fixed to said rock-shafts, cranks fixed to the opposite ends of each rock-shaft, stationary cams mounted adjacent to the opposite ends of said rotative frame and in position to operatively engage said cranks, for rocking the rock-shafts, a series of stationary scutching ribs mounted adjacent to said beater-arms and in position to extend circumferentially with respect to said supporting frame, and having a space between said ribs and
- said beater-arms adapted to admit material to be operated upon by the beater-arms, said scutching ribs being spaced apart and adapted to admit the outer extremities of the adjacent beater-arms therebetween, means for feeding material to be operated upon in position to be operated upon by the beater-arms, means for discharging the material, and means for rotating the rotative supporting frame.
14. In a machine for treating fibrous material, the combination of a rotative beater-arm-supporting frame mounted in suitable bearings, a series of peripheral rock-shafts each rockingly mounted in said rotative frame and in substantially parallel relation to the axis of the same, beater-arms fixed to said rock shafts, the main body of each of said beater-arms being arranged in position to extend outward from the axis of the rock-shaft with which it is connected and backward with respect to the direction of rotation of the beater-arms and said rotative supporting frame, crank and cam mechanism operatively connected with the rock-shafts, for rocking the same upon their axes, stationary concave scutching means extending over the rotative supporting frame and adapted to engage fibrous material passing over the said frame and the beater-arms supported by said frame, carrier mechanism mounted in position to engage and feed rearward material passing out from between said stationary concave scutching means and said rotative supporting frame, a rear stationary concave fiber-supporting member mounted intermediate the rotative supporting frame and said carrier and adapted to support fibrous material engaged by said carrier in position to be engaged and scutched by said beater-arms, and means for rotating the beater-arm-supporting frame.
15. In a machine for treating fibrous material, the combination of a rotative beater-arm-supporting frame mounted in suitable bearings, a series of peripheral rock-shafts each rockingly mounted in said rotative frame and in substantially parallel relation to the axis of the same, beater-arms fixed to said rock-shafts, the main body of each of said beater-arms being arranged in position to extend outward from the axis of the rock-shaft with which it is connected and backward with respect to the direction of rotation of said rotative supporting frame, means for rocking the rock-shafts upon their axes, stationary concave scutching means located adjacent to and in position to extend over said rotative supporting frame and adapted to engage and permit the passage of fibrous material over said frame and between said beater-arms and said stationary concave scutching means, means for feeding material into position to pass between said stationary concave scutching means and said

beater-arms, carrier mechanism mounted rearward with respect to said rotative supporting frame and adapted to engage and feed rearward material discharged from between said stationary concave scutching means and said rotative supporting frame, a rear stationary concave fiber-supporting member mounted adjacent to the discharge side of said rotative supporting frame and adapted to support fibrous material engaged by said rearwardly mounted carrier and in position to enable the said fibrous material to be engaged and scutched by said beater-arms, and means for rotating the beater-arm-supporting frame. 15
